DRIVE MECHANISM

Leonard M. Barker, North Syracuse, N. Y., assignor to General Electric Company, a corporation of New York

Application August 23, 1950, Serial No. 180,973

2 Claims. (Cl. 274—20)

1

This invention relates to drive mechanisms particularly applicable to transducing systems.

Recording and reproducing equipment usually comprises a transducing head which is brought into signal transfer relationship with a recording material. Where the intelligence is stored, or is to be stored in a plurality of tracks on the surface of the record material, means must be provided for driving the transducing head to scan the recording material surface. A special need exists in the case of repetitive, short-time transducing operations for a simple, inexpensive and reliable drive mechanism. Also, a drive mechanism which permits readily, minor adjustments of tracking motion and start-stop action of a transducing cycle is of special importance where rapid message changes are to be accommodated.

It is an object of my invention to provide novel means for imparting an axial shaft motion.

Another object of my invention is to provide novel means for imparting axial and rotational shaft motion.

Another object of my invention is to provide a novel drive mechanism and control for use in recording systems.

Another object of my invention is to provide a simple and inexpensive drive and control mechanism for effecting recording or playback of intelligence.

In accordance with an embodiment of my invention applicable to magnetic playback systems, a drive shaft carrying a pickup head at one end is mounted coaxially with a drive gear and arranged to rotate relative to the gear about its axis. A helical cam carried by the gear engages a mating cam or member carried by the shaft to cause axial displacement of the shaft relative to the gear when the gear turns, thereby causing the pickup head to scan a recording material surface. Friction forces developed between the helical cam and mating member during rotation of the helical cam provide contact pressure of the pickup head on the recording material. In addition, axial movement of the drive shaft is caused to operate a switch controlling drive gear operation.

The novel features which I believe characteristic of my invention are set forth with particularity in the appended claims. My invention, however, both as to its organization and method of operation, together with further objects and advantages thereof may best be understood by reference to the following description taken in connection with the accompanying drawing, wherein Fig. 1 illustrates in part-section the na-

2

ture of the drive mechanism and Fig. 2 illustrates schematically a detail of the arrangement of Fig. 1.

Referring to Fig. 1, there is disclosed a magnetic reproducing system for repeating messages of short duration whenever a switch is tripped. The switch may be tripped by a person opening a door, stepping on a mat, interrupting a light beam, dropping a coin in a vending machine, by the operation of a timing cam or other means. When the switch is tripped by some external means, not shown in the drawing, motor 1 is energized and drives an output shaft 2 by means of a helical gear 3. Attached to the output shaft 2 is a cylindrical drum 4 holding a length of magnetic material 5, such as a magnetic tape wrapped or deposited along its peripheral surfaces. A pickup head 6 rides on the tape and is given lateral motion by means of a cam arrangement, to be disclosed shortly, so as to traverse a helical track on the tape. In scanning the intelligence stored magnetically in the tape or record material 5, a small voltage is developed in the pickup head, amplified and applied to a speaker, not shown. When the pickup head 6 has moved sufficiently in a lateral direction, the shaft 7 to which it is attached opens a set of contacts 8 and 9 to stop the motor 1. By closing external switch 10 for a short time, the motor is reenergized to initiate a new cycle.

Referring to Fig. 1 in detail, motor 1 is caused to operate by supplying an alternating voltage over lead 11 directly to one terminal of the motor and over lead 12 through the normally closed switch contacts 8 and 9 to the other terminal of the motor. The motor 1 operates to drive helical gear 3 which causes output shaft 2 to rotate in the direction shown by arrow 13. Output shaft 2 passes through a bearing 14 carried in the housing 15 for supporting the drum 4 carrying the recording material 5 along its peripheral surface. The other end of the output shaft is supported in the bearing 16 press fitted in housing 15. A wing nut 17 engages the threaded end portion of output shaft 2 for rigidly forcing the drum 4, slipped over the output shaft, against the collar 18 secured to shaft 2. In a preferred embodiment, collar 18 has a protrusion which engages drum 4 to provide proper indexing of drum 4.

Idler gear 19, carried by shaft 20 mounted on housing 15, is driven by pinion gear 21 carried by shaft 2. In turn, idler gear 19 drives the cam gear 22 carried by the drive shaft 7. Thus, idler gear 19 imparts motion from gear 21 splined on shaft 2 to cam gear 22, which is constrained

to rotary motion about shaft 7 against bearing 23. Mounted coaxially with the cam gear is the drive shaft 7 carrying at one end the pickup head 6. Bracket 24 is supportedly mounted on the housing 15 for providing a bearing 25 by which the drive shaft 7 is supported at one end. At the other end, the drive shaft passes through bearing 23 carried by housing 15. Drive shaft 7 is arranged to be freely rotatable in bearing 23, relative to cam gear 22, and to be axially displaceable with respect to the cam gear. The cam gear 22, which is free to rotate on its shaft 7, has a 360° helical cam 26 cut on the end surfaces of its boss for engaging a mating cam or member linked to the drive shaft 7 by means of set screw 28. Since shaft 7 is prevented from rotating because of contact of pickup head 6 with drum 4, the two cams will move axially with respect to each other in accordance with the angular rotation of the cam gear 22. Upon completion of one revolution of shaft 7, the two cams 26 and 27 snap together to return the shaft axially to its original position. Although the preferred embodiment shown in Fig. 1 employs a helical driving and mating cam 26 and 27, respectively, one of the cams, for example 27, may be replaced with a stop, such as a pin protruding radially from the shaft 7. The radial and lateral motion of shaft 7 is still obtainable with this latter arrangement.

Rotation of the cam gear 22, riding against the bearing 23 in the housing 15, drives the mating cam 27 axially, thereby imparting lateral motion to the pickup head by means of drive shaft 7. To insure proper contact between the cams, and thereby insure proper lateral motion of the pickup head, the cams are spring loaded. Coil spring 29, mounted coaxially with the drive shaft 7, is mounted at one end on a shoulder 30 carried by mating cam 27 to keep the spring from interfering with the motion of shaft 7. A similar shoulder 31 is provided on the bearing 25.

As the cam gear 26 approaches the completion of one revolution, the mating cam or member 27 is arranged to push the shaft 7 to which it is fastened axially against fiber piece 32 carried by contact arm 33. As the contact arm 33 moves, contact 9, supported by 33, breaks with contact 8, thereby opening the motor energizing lead 12 and halting motor operation. Both contact arms 33 and 34 spaced by insulating washers 35 are mounted by means of a nut and bolt assembly 36 to spring leaf 37 supported by the switch bracket 25. The point at which the contacts 8 and 9 open may be adjusted by turning machine screw 38, threaded in the bracket 25. Thus, driving the machine screw towards the left causes the contacts to open earlier in the cycle, whereas driving the machine screw to the right causes the contacts to open later in the cycle. Thus, besides providing a simple and reliable scanning motion for the transducing head 6, the cam drive, together with a simple switch, provides a reliable means for coordinating motor operation with the transducing head positioning.

Referring to Fig. 2, it is seen that a reproduction cycle involves rotation of the drum 4 in the direction of the arrow concurrently with lateral motion of the pickup head 6 across the recording tape in the direction of the driving shaft 7. In addition to providing lateral motion to the pickup head, applicant's arrangement provides rotary motion of head 6 to bring it into and out of engagement with the magnetic material 5 carried on the surface of drum 4.

For this purpose, pickup head is carried by a radial member 39 secured to one end of shaft 7 by set screw 40. During rotation of the cam gear 22 in the direction of the arrow 44, friction between the face of cam gear 26 and the mating cam or member 27 tends to rotate the drive shaft 7, and hence also the pickup head in an angular direction, bringing the pickup head downward against the magnetic material on the surface of the drum. Sufficient pressure is exerted in this manner to maintain the pickup head against the tape in signal transfer relationship without interfering with the drum rotation. Just before the cams have snapped together, that is, just before member 27 is driven to its extreme position to the right, the drive shaft 7 causes contacts 8 and 9 to open, thereby deenergizing motor 1. Motor 1 coasts to a stop thereby preventing any further axial movement of the drive shaft.

If the recording cycle is to be repeated, switch 10 may be closed, thereby completing the energizing circuit to the motor and causing it to drive cam gear 22. Drive shaft 7 continues to move axially to the right until the remainder of 360° revolution of the cams 26 and 27 is completed, whereupon spring 29, now under compression, causes the cams to snap together thereby driving the drive shaft axially towards the left. In addition, the spring's developed torsional forces cause the drive shaft to rotate in a direction opposite to that shown by arrow 44, thereby withdrawing the head 6 from the tape surface. That is, the torsional forces of the spring in its compressed state overcome the normal friction forces existing between the cam faces to cause rotation of shaft 7 in a direction opposite to that depicted by arrow 44 until the cams snap together. Thereupon, these normal friction forces once again are effective in causing the pickup head to rotate against the drum surface. As mentioned before, this rotation is due to friction between the cam surfaces. This simple friction drive also permits the pickup head to be rotated out of the way when a tape change is desired.

By mounting the magnetic material on the surface of the drum, messages may be replaced by the simple expedient of unscrewing the wing nut, removing the old drum and inserting a new drum carrying the new message. Also, the drum loading permits different tapes to be applied to the same drum in a simple and expedient manner. The drum may be provided with a small groove on its rim slightly wider than the tape, and a radial slot formed in the rim. The tape is made slightly longer than the circumference of the drum and has sticky material on each end. One end of the tape is secured to the inside of the drum. It is then passed through a radial slot in the rim, around the drum in the groove, back through the slot and secured to the inside of the rim. To facilitate replacing the tape, the drum may be removed from the motor shaft. The discontinuity in the tape at the slot in the rim is not objectionable in playback provided the width of the slot is not excessive.

Since occasions may arise when tracking error is present, provision must be provided for moving the drum initially relative to the pickup head. In the arrangement of Fig. 1, this made possible by movement of an adjusting screw 41 threaded in spring leaf bracket 42 carried by housing 15. Lateral movement of the adjusting screw de-

termines the lateral position of the right-hand side of the output shaft 2. The output shaft 2 is driven by means of a helical gear 3 in a direction so that the action of the gears develops a small axial thrust to the right as shown by arrow 43. This thrust action causes the shaft 2 to bear against the edge of the adjusting screw, thereby positioning the drum with respect to the pickup head 6. Where it is more desirable to drive shaft 2 by means other than a helical gear, such as in friction or belt drives, a spring may be used to produce the end thrust developed by helical gear 3.

Modifications of this invention will occur to those skilled in the art, and it is desired to be understood, therefore, that this invention is not to be limited to the particular embodiments disclosed but that the appended claims are meant to cover all of the modifications which are within the spirit and scope of this invention.

What I claim as new and desire to secure by Letters Patent of the United States is:

1. Transducing apparatus comprising a cylindrical drum rotatable about an axis carrying on its surface a message recorded in a helical track, a driven member rotatable about an axis, a drive shaft positioned coaxially with said driven member and free to rotate relative to said driven member about said last named axis and free to move axially with respect to said driven member, means for driving said driven member and said drum about their respective axes, a transducing head carried by said shaft and free to rotate into engagement with said surface, a helical driving cam carried by said driven member, a mating member fixed to said shaft, and biased into frictional engagement with said cam for driving said shaft axially to cause said head to scan said surface, said frictional engagement creating a torque directed to press said transducer head into engagement with said surface carrying said message upon normal forward rotation of said driving means.

2. Transducing apparatus comprising a cylindrical drum rotatable about an axis carrying on its surface a message recorded in a helical track, a driven member rotatable about an axis, a drive

5 10 15 20 25 30 35 40

shaft positioned coaxially with said driven member and free to rotate relative to said driven member about said last named axis and free to move axially with respect to said driven member, means for driving said driven member and said drum about their respective axes, a transducing head carried by said shaft and free to rotate into engagement with said surface, a helical driving cam having a sudden discontinuity carried by said driven member, a mating member fixed to said shaft, and biasing means for biasing said mating member into frictional engagement with said cam for driving said shaft axially to cause said head to scan said surface, said frictional engagement creating a torque directed to press said transducer head into engagement with said surface carrying said message upon normal forward rotation of said driving means, said biasing means comprising a helical spring having one end in engagement with a stationary surface, and the other end engaging said shaft, said helical spring being wound in a direction so that upon said mating member reaching said discontinuity, with said helical spring in a compressed condition, said helical spring imparts a torque to said shaft directed to cause said transducer to lift from said surface.
